UNITED STATES PATENT OFFICE.

FREDERICK E. WALDEN, OF WORCESTER, MASSACHUSETTS, ASSIGNOR, BY MESNE ASSIGNMENTS, TO WALDEN-STAX MANUFACTURING CO., OF STONEHAM, MASSACHUSETTS, A CORPORATION OF MASSACHUSETTS.

WRENCH.

Application filed December 18, 1920, Serial No. 431,735. Renewed November 11, 1922. Serial No. 600,475.

To all whom it may concern:

Be it known that I, FREDERICK E. WALDEN, a citizen of the United States, and a resident of the city and county of Worcester and Commonwealth of Massachusetts, have invented certain new and useful Improvements in Wrenches, of which the following is a full, clear, and exact specification.

The object of this invention is the construction of a simple, inexpensive and convenient wrench of the ratchet type, the same being preferably formed from a single length of bar metal suitably bent to meet the purpose desired.

In doing this, I prefer to take a length of round wire rod, bend it substantially double to compose two nearly parallel arms, and form an elbow at the end of one arm with which the end of the other arm cooperates.

In the drawings forming part of this specification, Fig. 1 is a side view of one form of the wrench. Fig. 2 is a similar view of another form. Fig. 3 is a similar view of another modification. Fig. 4 is a similar view of a modification of the form shown in Fig. 3. Fig. 5 is a side view of a double ended form of the wrench. Fig. 6 is a cross section illustrating how channel iron can be used for the wrench, especially when of the form shown in Fig. 5.

The form of wrench shown in Fig. 1, which is my preferred construction, has its arm 1 substantially straight, merging in an easy semi-circular bend 2 into the arm 3. At the end of the arm 1 is an elbow 4 rising at practically right angles thereto and terminating in a lip 5.

The arm 3 is given an intermediate depression 6 into contact with the arm 1, and at this contact-point is formed a spur 7 engaging a spur or depression 8, for the purpose of preventing the arm 3 from yielding toward the bend 2, the lateral contact of the two arms serving to keep the arm-end 9 from approaching the arm 1, while still permitting recession therefrom.

For enabling the wrench to be used upon hexagonal nuts and bolt-heads, the elbow 4 is provided with the lip 5 above referred to, the latter not being of especial utility when the wrench is used with square headed bolts and square nuts, but inasmuch as the lip does not disqualify the wrench for its

latter use, I prefer to provide this lip for all the wrenches.

Instead of intermediately depressing the arm 3 as set forth in Fig. 1, the arm may have its end portion bent sharply downward and toward the bend 2, as at 10, the remainder of the arm being straight. The end of this elbow 10 may be adapted to engage a notch 11 in the arm 1, thereby acting both to prevent further approach of the arm 3 toward the arm 1, and to keep the arm 3 from creeping toward the bend 2 by the latter's yielding.

In the structure illustrated in Fig. 3, a part of the arm 3 is prolonged, as at 12, which prolongation terminates in a shoulder 13 immediately beyond the elbow 4, thereby providing means for preventing the approach of the arm 3 toward the arm 1, for preventing the arm 3 from longitudinal yielding, and also for ensuring the elbow 4 against bending away from the arm-end 9.

In the construction shown in Fig. 4, the prolongation 12 is bent outward slightly to make room for the lip 5, but the same is otherwise similar to that of Fig. 3.

Fig. 5 shows the wrench formed with actuating means at both ends, and composed of two bars 14 and 15 secured together at their mid-length by spot-welding, as at 16, or otherwise, but the wrench elements 4, 5, 7 and 8 are substantially the same as above described.

Instead of using round rod for the wrench, channel iron 17 may be utilized, and if used for the double wrench shown in Fig. 5, the two channel iron bars can be fastened together by means of rivets 19, as shown in Fig. 6.

In using the wrench for square headed bolts, the corners 20, 21 thereof rest against the end 9 and base of the elbow 4, as shown in Fig. 1, when the bend 2 is forced in the direction of the arrow. Since neither of said parts will yield to ordinary strains, the bolt will be forcibly turned; but when the wrench handle is forcibly swung in an opposite direction to the arrow, the arm-end 9 will move away from the arm 1 and will fail to turn the bolt, thus performing its ratchet function.

When used upon a hexagon nut or bolt-head, the lip 5 serves to ensure against the slipping of such nut or head, either out

from between the wrench jaws, or from its turning therein.

The structure shown in Figs. 3 and 4 provides what is termed a "box" wrench, that is, one which entirely surrounds the nut or bolt-head and consequently will not drop off therefrom when not under control.

When provided with the engaging shoulders or spurs 7 and 8, the arm 3 cannot yield against a powerful turn applied to a nut or bolt, by the slight unbending of the curve 2, but will stand up against sufficient force to twist a bolt in two; and since the force applied to the elbow 4 comes against it close to its juncture with the arm 1, it also is able to resist practically any force.

What I claim is:

1. A wrench comprising two resiliently united but substantially parallel members, one having an elbow at its outer extremity, and the other presenting its end to the outer part of said elbow but spaced therefrom, means being provided for preventing said elbow from being bent away from the end surface of the other member.

2. A wrench comprising two resiliently united but substantially parallel members, one having an elbow at its outer extremity,

and the other presenting its end to the outer part of said elbow but spaced therefrom, the latter having a part thereof adapted to contact with the other member to prevent approach and also longitudinal displacement of the two members in one direction.

3. A wrench comprising two resiliently united but substantially parallel members, one having an elbow at its outer extremity, and the other presenting its end to the outer part of said elbow but spaced therefrom, the latter having an intermediate portion bent into contact with the other member, the two contacting surfaces being formed with shoulders to prevent longitudinal displacement of the two members in one direction.

4. A wrench comprising two resiliently united but substantially parallel members, one having an elbow at its outer extremity, and the other presenting its end to the outer part of said elbow but spaced therefrom, means being provided for preventing the approach but not the recession of said members, said elbow having a lip at its end.

In testimony that I claim the foregoing invention, I have hereunto set my hand this 16th day of December, 1920.

FREDERICK E. WALDEN.
